CLAIM

We claim the ornamental design for an accessory support bracket, as shown and described.

DESCRIPTION

FIG. 1 is a top, front, left perspective view of the accessory support bracket showing our new design;

FIG. 2 is a top, rear, right perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof; and,

FIG. 8 is a bottom plan view thereof.

In the drawings, the broken lines depict portions of the accessory support bracket that form no part of the claimed design.
